[57] **ABSTRACT**

Apparatus for controlling the placement of split die cavities in a progressive die where each cavity is described in terms of a group of contour coordinate signals which define predetermined coordinates of the contour of the cavity and split direction signals which define faces of the cavity contour from which splits thereof radiate, the apparatus comprising:

first register means for storing a first group of contour coordinate signals and split direction signals corresponding to a first split die cavity;
second register means for storing a second group of contour coordinate signals and split direction signals corresponding to a second split die cavity;

analyzer means responsive to first and second contour coordinate signals for determining whether the split die cavity corresponding to a first signal group is inappropriately placed with respect to the split die cavity corresponding to a second signal group because of unmatched split conditions.

**METHOD AND APPARATUS FOR CONTROLLING
PLACEMENT OF SPLIT DIE CAVITIES**

**CROSS-REFERENCES TO RELATED
APPLICATIONS**

This application refers to copending U. S. Application Ser. No. 66,533 filed by Richard C. Levine on August 24, 1970, and entitled "Automatic Method and Apparatus for Fabricating Progressive Dies" and another copending application filed by Daniel G. McFadden and Richard C. Levine on Aug. 30, 1972 and entitled "Method and Apparatus for Automatic Optimal Layout of Shapes to be Cut from Material," U. S. Application Ser. No. 284,879, both of which are hereby incorporated herein by reference.

BACKGROUND OF THE INVENTION

This invention relates to the automatic design of progressive dies and, in particular, to a method and apparatus for determining if an unmatched condition of die splits is present at a particular station of such dies.

In the above copending application, Ser. No. 66,533, there is disclosed a method for the automatic design of progressive dies in which the various cavities are distributed along the progressive stations of the die in accordance with a sufficient spacing to permit adequate metal between the cavities in relation to the cutting forces of the cavities.

In some types of die construction, this alone is a sufficient criterion for the placement of the cavities. This is true, for example, if the method of machining allows an isolated complicated hole to be made in the die section, as is the case with Electric Discharge Machining (EDM), or drilling and hand filing or broaching methods. However, it is frequently desirable to "split" the cavity, and construct the die segments by grinding each section with an abrasive wheel so that two or more segments of the die each contain a portion of the contour of the particular cavity. When all these segments are properly assembled, they all are adjacent to the cavity which then has several splits radiating from it. These splits may go to the outer edges of the die or may terminate on other cavities in the die.

The point(s) on the cavity contour where the splits occur is governed by machining considerations and the shape of the cavity. It is not feasible to split a cavity so that deep or inaccessible recesses occur in one of the portions since it is not possible to get a grinding wheel into these recesses. Thus, for example, a horizontally long, rectangular cavity would be split by a horizontal line through the left and right ends. Similarly, a vertically tall, rectangular cavity would be split by a vertical line through the top and bottom. More complex shapes may, in general, require more than two points of splitting. In addition, the split generally radiates away from the contour at right angles to the edge at the point of splitting into avoid producing acute points or corners on the die sections.

Because the die cavities cannot be split arbitrarily, certain placements of die cavities in the die are not feasible. These are the placements which would not geometrically permit split radiating from one cavity to terminate on the facing contours of a second nearby cavity. Thus, for example, the two cavities described above could not be placed in close proximity, side by side, since the horizontal split radiating from one cavity can-

not terminate on the facing side of the second cavity. A top-to-bottom, vertical split, or some suitable additional cavity(ies) must intervene to allow a proper termination of the horizontal split. In this case, the vertical split through the other cavity can terminate on the top and bottom edges of the die structure.

Similarly, the two cavities cannot be placed in close proximity, one above the other, since the vertical split through the tall cavity cannot terminate on the facing side of the second cavity. Again, the placement of a suitable intervening horizontal split or additional cavity would produce a permissible construction. However, it should be noted that such intervening splits or cavities may not fit into the space between the two original cavities, and thus the entire attempted placement is not feasible.

Heretofore, the design of dies has been done entirely by skilled human die designers making mental judgments based on knowledge and experience.

SUMMARY OF THE INVENTION

It is an object of this invention to provide an automatic method and apparatus for placing cavity contours within a die structure taking into account the proximity and direction of splits radiating from cavities.

A further object of this invention is to provide a method and apparatus for indicating the result of a "go-no-go" test for a tentative position of a contour in the form of a signal from an independent mechanism which can be flexibly incorporated into various different structures used in the automatic design of dies.

Other objects and advantages of this invention will become apparent upon reading the appended claims in conjunction with the following detailed description and the attached drawing.

BRIEF DESCRIPTION OF THE DRAWING

FIG. 1 is a block diagram of an illustrative overall system in accordance with this invention.

FIG. 2 is a block diagram of an illustrative analyzer circuitry as used in FIG. 1.

FIG. 3 is a schematic diagram of an illustrative one of the analyzer units of the analyzer circuitry of FIG. 2.

FIG. 4 is a block diagram of an illustrative switching and control circuit as used in FIG. 1.

FIG. 5 is a diagrammatic illustration indicating the operation of the analyzer units of FIG. 3.

**DESCRIPTION OF THE PREFERRED
EMBODIMENTS**

In the automatic design of dies, the various die cavity contours must be distributed across the die by translating each contour to a particular stage or station. This consists of moving the contour horizontally by an integral number of "feed" or "jump" distances. The "feed" distance is equal to the distance that the metal strip or ribbon is horizontally moved during the operation of the completed die.

The number of splits radiating from a cavity may be zero (for a hole made by drilling or EDM) two, three, four, or more. It is not meaningful to have only one split radiating from a cavity since this would not allow the metal segments surrounding the cavity to be separated to give access for a grinding wheel to shape the cavity.

Referring to FIG. 1, the overall system of the invention comprises storage device 10 for storing coordinate describing signals to define each cavity contour and the number and direction of splits radiating therefrom. The store 10 may also be used for storing a contour translated to a particular stage or station of the die by adding, to the x-coordinate signals, a quantity representing the numerical product of the feed distance and the stage number.

There is also switching and control circuitry 16 for directing the signals representing the coordinates and split faces to analyzer circuitry 18 for the purpose of determining if any contours do not have matching splits conditions on their facing edges. The feed is stored in storage device 12 and the stage number is stored in a multi-celled device 14, the number of cells corresponding to the number of storage locations in store 10.

The system of FIG. 1 may be used by other equipment in a process of sequential operation whereby the other equipment would set the stage numbers of the various contours and use the output of the FIG. 1 system to determine if the arrangement of the contours indicated by the stage numbers is not feasible due to a mismatch of splits as described hereinbefore. This test is typically used in addition to other test concerned with physical closeness of contours, and other factors (as described in copending Application Ser. No. 66,533) to eventually select a configuration which meets all conditions for die construction.

In this system, the coordinates for the contour may take many forms of varying complexity. For the purpose of illustration, any contour may be adequately represented by four coordinates which respectively represent the maximum and minimum x-coordinates and maximum and minimum y-coordinates of the contour. These are represented by the letter symbols X_r , Y_r , X_n , Y_n , respectively, in FIG. 1. These numerical coordinates may be stored as capacitor cell (or other signal) voltages proportional to the coordinate, or they may be represented digitally and stored in binary form in a magnetic core memory, as well as in other forms. For the purpose of the operation of this structure, the coordinates are stored as analog voltages proportional to the numerical value of the coordinate.

The information describing the faces from which the splits radiate can also be represented adequately by considering only four directions, labelled as Right, Left, Top and Bottom (R, L, T, and B, respectively, in FIG. 1). The four cells used to represent these directions can be used in essentially a binary mode, in which a voltage which is non-zero represents a split emerging from the particular face and a voltage of zero represents the fact that no split emerges from that face. Thus, a positive, non-zero voltage will be stored in the appropriate storage cell to represent a split emerging from that face.

It should be understood that, in general, more than four coordinates and four directions can be used. However, in this case, a total of eight cells are needed to represent the data describing each contour and its splits.

It should also be noted that the values do not actually have to be stored in cells for this purpose so long as they are available to the system when needed. Thus, for example, the values could be re-derived from the basic description of the complete contour coordinates by a scan of the contour each time the values are needed.

This derivation of the maximum and minimum values by scanning is shown in detail in both of the hereinbefore mentioned copending applications.

The overall structure of the system is shown in FIG.

5 1. The values describing the coordinates and split directions of each contour are stored in storage device 10 which comprises a bank of storage cells, organized into groups of 8 cells. These 8 cells store the values respectively of the horizontal maximum and minimum (X_r and X_n) and the vertical maximum and minimum (Y_r and Y_n) and the indicators for splits in four directions: Right Left, Top and Bottom (R, L, T, and B).

10 15 The bank of cells 10 is connected to analyzer circuitry 18 by switching and control circuitry 16 which contains, inter alia, a simple multiplier and adder. Circuitry 16 directs signals from and to the various storage cells 10, 12 and 14, the input terminal 20, an analyzer circuitry 18.

15 20 Reference should now be made to FIG. 4 for a more complete description of circuitry 16. Switching and control circuitry 16 may comprise a bi-directional scanner 22 (the input and output connections thereto being simplified for ease of description of circuitry 16) whereby input information from terminal 20 characterizing the contours is successively stored in the groups 10a, 10b, 10c... and 14a, 14b, and 14c... of the stores 10 and 14 as the scanner 22 is successively stepped. The feed is also stored in feed store 12.

25 30 A next mode of operation involves the actual coordinates of the contours are determined. That is, each contour is horizontally translated to its tentative station. This is accomplished by successively reading the contour characterizing information from the stores 10 and 14 by scanner 22. Each stage or station numbers from store 14 is applied to multiplier 24 through switch 26 which would be closed at this time. The feed is applied to multiplier 24 over line 28. The resulting product, which is the distance the horizontal coordinates

35 40 must be translated, is applied to adder 30 over line 32. Also applied to adder 30 are the initial horizontal coordinates of the contour being currently scanned by the scanner 22. These coordinates, which define the horizontal position of the cavity or contour if it were located in the first stage of the die, are applied over line 34 through switch 35, which would be closed at this time. The resulting sum, which is the horizontal coordinates of the contour translated to the station represented by the number in station store 14 is stored back

45 50 55 60 in store 10 through switch 38 and scanner 22. Thus, after the scanning operation is completed, all the horizontal coordinates of each contour, having a non-zero stage number, will have been translated to the stage number assigned thereto and restored in store 10. In some applications, a contour is not assigned a stage number until it is ready for testing. In other applications, all contours are initially assigned stage numbers and the system of this invention is used to determine if any cavities with conflicting splits are present.

65 60 In a next mode of operation, the actual testing of one or more of the contours occurs to determine if conflicting splits are present. Thus, if a predetermined contour is to be tested such as that stored in cell group 10c. Preset means 40 would be utilized to step scanner 22 to select this contour and store in it register 42 over line 44 through switch 46, which would be closed at this time.

The scanner 22 is then reset to scan all the contours stored in store 10 together with their associated stage numbers stored in store 14. The stage numbers are successively tested at blocks 48 and 50 to determine if the contour being currently scanned:

(1) has been assigned a zero stage number (which, as stated before, means that the contour is not to be tested at this time), or (2) is the same as the contour previously stored in register 42. If the contour being currently scanned does not satisfy either of the above tests, it is applied to register 52 over line 54 where it is compared with the contour stored in register 42 in analyzer 18. The manner of comparison will be described in more detail hereinafter with respect to FIGS. 2 and 3. Each contour in store 10 may be stored with the other contours stored therein in the manner described above.

Thus, in summary, the operation of circuitry 16 is as follows:

1. The signals representing the coordinate and split directions of each contour are directed to and stored in the appropriate stores 10. 2. The feed and stage numbers of each contour are directed from input terminal 20 to the appropriate stores 12 and 14. 3. The scanner 22 scans along the groups describing the coordinates and split directions, and the cells describing the stage number, of each contour. In each group, the switching and control circuitry 16 senses the value of the two x -coordinates and adds to them the product of the feed and the stage number, as produced by the multiplier 24 and adder 30 in the switching and control circuitry. At this point, the coordinates stored in the stores 10 represent the disposition of the contours across the surface of the die. Contours not involved in the test are those with a stage number value of zero. 4. The scanner 22 scans along the groups describing the coordinates and split directions, directing those signals to the analyzer circuitry 18 for comparison with the corresponding signals from the contour under the test, which is stored in register 42 an input signal from preset means 40 may specify which contour number is to be used constantly for the test comparison. The switching and control circuitry 16 selects each group (except those with a stage number of zero, and the comparison group itself).

The analyzer circuitry 18 will produce no output if all the comparisons show valid combinations of facing splits. If an invalid combination occurs, an output signal will be produced to indicate that the tentative position of the test contour is not consistent with the other contours on the basis of the facing edges having unmatched presence or absence of splits.

The internal operation of analyzer circuitry 18 and its connection to the registers 42 and 52 will be described in detail after some further discussion of the use of this system in automatic die design. Typically, at an intermediate stage of the process of die design, some of the contours have been placed at a definite stage or station of the die. Others (designated by a stage number value of zero) have not, and one of these would be tentatively tested at various stages to discover where it will fit. The first test might be on the basis of closeness to other placed contours in terms of geometrical distance, strength of materials analysis, or both. Once a tentative stage is found which is feasible on the basis of the foregoing analysis, the equipment described in this specification would be employed to insure that the tentative

placement of the particular contour is feasible on the basis of the matching of splits.

The precise connections produced by the switching and control equipment are shown in FIG. 2. The registers 42 and 52, respectively, correspond to the comparison group and one of the other groups (for example, 10c) from the coordinate and split direction memory storage 10. The connections from various cells in the registers 42 and 52 to the terminals of four internal analyzer units 56-62 are shown by schematic wiring lines for the first analyzer unit 56 and in the interest of clarity, the connections to the other three units 58-62 are indicated by lettering on the terminal of the analyzer unit to show which cell is connected there. The outputs of the four analyzer units are connected, through diodes, to a common output terminal 64.

The circuitry comprising analyzer units 58-62 is shown in FIG. 3. Each analyzer unit has eight input terminals 66-80 as can be seen in FIGS. 2 and 3. The input terminals are connected to difference amplifiers 82-90, each of which has an output voltage proportional to the algebraic difference between the input signal at its plus and minus input terminals. Thus, the output signal of difference amplifier 82 will only be positive when the signal at terminal 66 is algebraically greater than the signal at terminal 68.

Terminals 78 and 80 are cross-connected to the inputs of difference amplifiers 88 and 90, so that one of the two amplifiers will produce a positive output if the signals at terminals 78 and 80 are different, no matter which of the signals is greater than the other. Thus, amplifiers 88 and 90 perform an EXCLUSIVE OR function.

The output of amplifiers 82 through 90 are respectively connected through small, equal resistors R_A to clamping diodes and a clamping voltage supply, V_c . Thus, the output voltage at this point will not exceed V_c even if the input signals differ by an amount much greater than the minimal difference corresponding to the output value of V_c . The five respective clamped outputs of the difference amplifiers 82 through 90 are connected through the five equal resistors, R_A , to a common node 102. This node is connected to the output through diode 104 and to a negative reference voltage, $-V_n$, through a resistor R_B . The values of the resistors R_A and R_B are so chosen that a clamped voltage of V_c emerging from any four or more of the five difference amplifiers will produce a positive voltage at node 102, and a consequent signal can pass through output diode 104. For example, if V_c is 1 volt and $-V_n$ is -3.5 volts, the values $R_A = 1,000$ ohms and $R_B = 1,000$ ohms would be suitable illustrative values for this purpose.

The operation of the analyzer units as shown in FIGS. 2 and 3 is as follows: If as is shown in FIG. 5, the contour B is completely to the left of the contour A, neither contour is completely above or below the other, and the facing edges have unmatched split conditions (i.e., a split on one contour pointing toward the other with no corresponding split pointing back), an output signal will be produced by analyzer unit 56. Thus, in FIG. 5, $X_{AN} > X_{BN}$ indicating that B is completely to the left of A. This is detected by difference amplifier 82 whereby at least one volt is applied to node 102 (assuming the illustrative values specified hereinbefore are used). $Y_{AN} > Y_{BN}$ and $Y_{BN} > Y_{AN}$ and thus neither contour is completely above or below the

other. These two conditions are detected by difference amplifiers 84 and 86, respectively, whereby at least two more volts are applied to node 102. Since there is no R_B (a split from the right side of B) and there is a L_A (a split from the left side of A), the EXCLUSIVE OR function of difference amplifiers 88 and 90 is satisfied whereby one more volt is applied to node 102, making the total voltage, four volts. Thus, an output voltage is applied to output terminal 64 indicating that an unmatched condition has occurred. This indication may be used in several ways, such as described hereinbefore.

The other three units 58-62 produce output signals if a similar situation exists with B to the right of A, below A, and above A, respectively, as can readily be determined by an inspection of FIG. 2.

It would be obvious to one skilled in the electronics and control art that a implementation of these same tests is possible using entirely digital equipment and computing and storing all values utilized in the analog circuitry in a read-write memory under the control of wired or stored program step control signals. The extension of the four coordinate examples to the use of further coordinates and directions merely require the addition of similar circuit elements in the analog case, or further repetitions of operations in the purely digital case.

Numerous modifications of the invention will become apparent to one of ordinary skill in the art upon reading the foregoing disclosure. During such a reading, it will be evident that this invention provides a method and apparatus for controlling placement of split die cavities for accomplishing the objects and advantages hereinstated.

What is claimed is:

1. Apparatus for controlling the placement of split die cavities in a progressive die where each cavity is described in terms of a group of contour coordinate signals which define predetermined coordinates of the contour of the cavity and split direction signals which define faces of the cavity contours from which splits thereof radiate, said apparatus comprising:

first register means for storing a first group of contour coordinate signals and split direction signals corresponding to a first split die cavity;
second register means for storing a second group of contour coordinate signals and split direction signals corresponding to a second split die cavity;
analyzer means responsive to first and second contour coordinate signals for determining whether the split die cavity corresponding to said first signal group is inappropriately placed with respect to the split die cavity corresponding to said second signal group because of unmatched split conditions.

2. Apparatus as in claim 1 including first storage means for storing a plurality of said groups of contour coordinate signals and split direction signals including said first and second groups of contour coordinate signals and split direction signals; and

means for selecting said first group of contour signals from said plurality of groups and storing said first group in said first register means;
means for scanning the remaining groups of said plurality of groups and successively applying said remaining groups to said second register means;
said analyzing means being successively responsive to said first and second register means for determin-

ing whether the split die cavity corresponding to said first signal group is inappropriately placed with respect to the other split die cavities corresponding to said remaining groups because of unmatched split conditions.

3. Apparatus as in claim 2 where said scanning means includes means for successively initially storing in said first storage means a plurality of groups of initial contour coordinate signals respectively corresponding to said plurality of groups of contour coordinate signals, said apparatus including:

second storage means for storing a plurality of stage numbers respectively corresponding to the stage numbers of the split die cavities corresponding to said plurality of initial contour coordinate signals;

third storage means for storing the feed distance between stages of the progressive die;
translating means successively responsive to said initial contour coordinate signals, said stage numbers and said feed distance for translating the horizontal coordinates of each initial group of contour coordinate signals to its corresponding stage so that the resulting group of signals corresponds to the contour coordinate signals for that stage.

4. Apparatus as in claim 3 wherein said translating means includes:

multiplier means for successively multiplying said stage numbers by said feed distance, the successive products respectively corresponding to the horizontal distances said horizontal coordinates of the initial groups should be translated; and
adder means for successively adding said successive products and said last-mentioned horizontal coordinates to obtain said plurality of contour coordinate signals.

5. Apparatus for controlling the placement of split die cavities in a progressive die where each cavity is described in terms of a group of contour coordinate signals which define predetermined coordinates of the contour of the cavity and split direction signals which define faces of the cavity contour from which splits thereof radiate, and apparatus comprising:

first register means for storing a first group of contour coordinate signals and split direction signals corresponding to a first split die cavity;
second register means for storing a second group of contour coordinate signals and split direction signals corresponding to a second split die cavity;
analyzer means including;

contour comparing means for comparing said first and second contour coordinate signals to determine the relative spatial relation of said first and second split die cavities with respect to one another; and

split comparing means for comparing said first and second split direction signals to determine whether a split is directed toward either said first or second die cavity without a corresponding split being directed back;

decision means responsive to said contour comparing means and said split direction comparing means for determining whether the split die cavity corresponding to said first signal group is inappropriately placed with respect to the split die cavity corresponding to said second signal group because of unmatched split conditions.

6. Apparatus as in claim 5 where said contour comparing means comprises a plurality of groups of comparing units where each group of comparing units determine if a predetermined spatial relation exists between said first and second die cavities.

7. Apparatus as in claim 6 where said split comparing means comprises a plurality of EXCLUSIVE OR means respectively associated with said plurality of groups of comparing units.

8. Apparatus as in claim 7 where said decision means comprises a plurality of detecting means respectively responsive to said plurality of groups of comparing units and said plurality of EXCLUSIVE OR means for determining if said unmatched condition exists at any one of the predetermined spatial relationships between 15 said first and second die cavities.

9. A method for controlling the placement of split die cavities in a progressive die where each cavity is described in terms of a group of contour coordinate signals which define predetermined coordinates of the 20 contour of the cavity and split direction signals which define faces of the cavity contour from which splits thereof radiate, said method comprising:

storing a first group of electrical contour coordinate signals and electrical split direction signals corresponding to a first split die cavity; 25

storing a second group of electrical contour coordinate signals and electrical split direction signals corresponding to a second split die cavity;

analyzing said first and second contour coordinate 30 signals to determine whether the split die cavity corresponding to said first signal group is inappropriately placed with respect to the split die cavity corresponding to said second signal group because of unmatched split conditions. 35

10. A method as in claim 9 including:

storing a plurality of said groups of contour coordinate signals and split direction signals including said first and second groups of contour coordinate signals and split direction signals; and 40

selecting said first group of contour signals from said plurality of groups;

scanning the remaining groups of said plurality of groups;

said analyzing step determining whether the split die 45 cavity corresponding to said first signal group is inappropriately placed with respect to the other split die cavities corresponding to said remaining groups because of unmatched split conditions.

11. A method as in claim 10 including the steps of initially storing a plurality of groups of initial contour coordinate signals respectively corresponding to said plurality of groups of contour coordinate signals; 50

storing a plurality of stage numbers respectively corresponding to the stage numbers of the split die cavities corresponding to said plurality of initial contour coordinate signals;

storing the feed distance between stages of the progressive die;

translating in successive response to said initial contour coordinate signals, said stage numbers and said feed distance, the horizontal coordinates of 60

each initial group of contour coordinate signals to its corresponding stage so that the resulting group of signals corresponds to the contour coordinate signals for that stage.

5 12. A method as in claim 11 where said translating step includes:

successively multiplying said stage numbers by said feed distance, the successive products respectively corresponding to the horizontal distances said horizontal coordinates of the initial groups should be translated; and

successively adding said successive products and said last-mentioned horizontal coordinates to obtain said plurality of contour coordinate signals.

13. A method for controlling the placement of split die cavities in a progressive die where each cavity is described in terms of a group of contour coordinate signals which define predetermined coordinates of the contour of the cavity and split direction signals which define faces of the cavity contour from which splits thereof radiate, said apparatus method comprising:

storing a first group of electrical contour coordinate signals and electrical split direction signals corresponding to a first split die cavity;

storing a second group of electrical contour coordinate signals and electrical split direction signals corresponding to a second split die cavity;

analyzing said first and second contour signals and said first and second split direction signals, including the steps of:

comparing said first and second contour coordinate signals to determine the relative spatial relation of said first and second split die cavities with respect to one another; and

comparing said first and second split direction signals to determine whether a split is directed toward either said first or second die cavity without a corresponding split being directed back;

deciding from said contour comparing step and said split direction comparing whether the split die cavity corresponding to said first signal group is inappropriately placed with respect to the split die cavity corresponding to said second signal group because of unmatched split conditions.

14. A method as in claim 13 where said contour comparing step comprises a plurality of groups of comparing steps where each group of comparing steps determines if a predetermined spatial relation exists between said first and second die cavities.

15. A method as in claim 14 where said split comparing step comprises a plurality of EXCLUSIVE OR steps respectively associated with said plurality of groups of comparing steps.

16. A method as in claim 15 where said deciding step comprises a plurality of detecting steps respectively responsive to said plurality of groups of comparing steps and said plurality of EXCLUSIVE OR steps for determining if said unmatched condition exists at any one of the predetermined spatial relationships between said first and second die cavities.
